(Cl. D3—25)

To all whom it may concern:

Be it known that I, Lucy Larssen, a citizen of the United States of America and a resident of New York city, county of New York, State of New York, have invented a new, original, and ornamental Design for a Blouse or Similar Article, of which the following is a specification, reference being had to the accompanying drawings, forming part thereof.

Fig. 1 is a front view of a blouse, showing my new design;

Fig. 2 is the rear view thereof; and

Fig. 3 is an enlarged detail of the collar.

I claim:

The ornamental design for a blouse or similar article, substantially as shown.

LUCY LARSEN.
